M. H. PÉREZ

PHONOGRAPH RECORD REPEATER

Filed Oct. 8, 1923

INVENTOR:
Manuel Humberto Pérez,
BY

C. C. Kines, ATTORNEY.

UNITED STATES PATENT OFFICE.

MANUEL HUMBERTO PÉREZ, OF SAN PEDRO SULA, HONDURAS.

PHONOGRAPH-RECORD REPEATER.

Application filed October 8, 1923. Serial No. 667,340.

To all whom it may concern:

Be it known that I, MANUEL HUMBERTO PÉREZ, a citizen of the Republic of Honduras, residing at San Pedro Sula, in the 5 Department of Cortez and Republic of Honduras, have invented new and useful Improvements in Phonograph-Record Repeaters, of which the following is a specification.

10 This invention relates to a phonograph record repeater, or device for attachment to talking machines whereby a record may be repeatedly played, the primary object of the invention being to provide a device of 15 this character which is simple and inexpensive in construction, reliable and efficient in operation, and pleasing in shape and appearance so as to constitute an adjunct to the machine which may be made 20 as ornamental and attractive as desired, according to the taste or fancy of the manufacturer or of the person purchasing the same for use.

25 A further object of the invention is to provide a device of the stated character which may be employed in connection with all sizes and kinds of records and various makes of talking machines.

30 The invention consists of the features of construction, combination and arrangement of parts, hereinafter fully described and claimed, reference being had to the accompanying drawing, in which:—

35 Figure 1 is a top plan view of a phonograph record repeater embodying my invention.

40 Figures 2, 3 and 4 are sections taken, respectively, on the lines 2—2, 3—3 and 4—4 of Figure 1.

45 Figure 5 is an enlarged plan view of the slide-block or head and slotted yoke, showing the adjusting nut in section.

50 Figure 6 is a section on line 6—6 of Figure 1.

55 In the practical embodiment of my invention, as herein disclosed, I provide a record repeater comprising a member 1 in the form of a plate made of sheet metal or other sheet material suitable for the purpose. This member 1 has a curved or arcuate body portion 2 terminating at one end in diverging flukes or wings 3 and 4 united by a substantially V-shaped or triangular web 5 constituting a widened por-

tion of the fluke. At the opposite end of 55 the body portion 2 is a curved or offset arm 6 defining a recess 7 designed to receive the needle or stylus of the sound box of the phonograph when said needle is in starting position. The body portion 60 2 is of substantially uniform width between its end or extremity 8 from which the arm 6 projects and the point 9 from which the plate is widened to form the wings or flukes 3 and 4 and the intermediate web or expanded plate portion 5. Rails or guide ribs 10 and 11 extend upwardly from the plate and form a guide groove for guiding the needle so as to return the sound box or reproducer from the final groove or 65 finishing point on a record to the first groove or starting point on a record for a repetition of the composition to be played. These rails are relatively close together and extend substantially in parallel relation 70 along the portion 2 of the repeater, providing a delivery groove 12 which is of substantially uniform width except at the point where it merges into the recess 7, at 75 which point the rails 10 are slightly flared 80 to permit the needle to move easily into said recess 7 and engage the proper groove in the record exposed thereby. From the point 9 the rails 10 and 11 diverge as shown at 10' and 11' and extend along the widened 85 portion 5 of the plate adjacent to the margins thereof and thence to the extremities of the flukes or wings 3 and 4, forming guards to prevent displacement of the 90 needle from the repeater after it becomes initially engaged therewith. The divergent portions 10' and 11' of the rails are sufficiently spread to provide with the edge portion 13 of the web 5 a flaring mouth 95 or entranceway to the groove which is sufficiently wide to engage and receive the needle at any position which it may have in the final groove of a record of any size and to conduct the same to said groove 100 for the return of the needle to the starting point. As a result of the construction described, the flaring initial point of the groove gradually converges toward the return portion 12 of the groove, so that the 105 needle will be conducted from any finishing position which it may occupy at the completion of the playing of the composition to the recess 7, at which point the needle

will again engage the starting groove of the record. The edge 13 is preferably provided with a beveled or sloping surface, as shown in Figure 6, to permit the needle 5 to ride easily up upon the plate 5.

The wing or fluke 3 is provided with a neck portion 14 rigidly connecting the same with a longitudinally slotted spring metal yoke 15 in which is slidably fitted a head block 16. This head block is formed with an opening 17 for the reception of the spindle of the turntable of the machine, whereby the repeater is adapted to be fitted on said spindle. The block is also provided with a tubular friction grip member or ferrule 18 slotted to provide a series of spring grip fingers 19, which ferrule receives the spindle and which fingers are slightly pressed inwardly to frictionally engage the spindle under their spring pressure. This spring pressure is sufficient to adapt the repeater to be coupled to the spindle to rotate therewith and with the turntable of the phonograph at times, and also serves as a slip-clutch which engages the spindle lightly enough to adapt the repeater to be held stationary while the record is rotating with the turntable in the playing of the composition. The head block 16 is adjustable in the slotted guideway of the yoke 15 so as to regulate its position with respect to, or distance from, the recess 7, so that the repeater may be adjusted with relation to the spindle and center of the record to dispose the recess 7 so as to overlie or register with the starting groove of a record of any kind. The yoke 15 is slit at one end to form the resilient yoke arms 20, and the free ends of these arms are normally slightly spread by their spring action and are formed with threaded half-bosses providing a divided screw 21 to receive an internally tapered cap nut 22, adapted to be adjusted outwardly and inwardly so as to permit the arms 20 to spread and release the head 16 when it is desired to adjust the same, and so as to adapt said yoke arms to be contracted to firmly and securely clamp the head in adjusted position. The arm 6 is provided with a sleeve 23 in which is fitted an adjustable stop rod 24 having an inner beveled end portion 25 and provided at its outer end with an adjusting knob 26. This rod 24 is provided with a spiral groove 27 to receive the point of a set screw 28 on the sleeve. When this set screw is slightly relaxed the rod 24, through its threaded connection therewith, may be adjusted inwardly and outwardly, and then by tightening the screw the rod may be firmly clamped in adjusted position. This rod is provided for engagement with the needle of the sound box to hold the repeater from rotation with the record while the composition is being played, and is adjustable to dispose its tapered end 25 to register with the final groove of a rec-

ord of any size or diameter, so as to release the repeater for rotation with the record when the needle reaches the final groove at the end of the composition.

In the operation of the device, the repeater is arranged to rest upon the record and its head 16 engaged with the turntable spindle, and the yoke 15 and stop rod 24 adjusted to dispose the recess 7 in line with the starting groove and the tapered end of the stop rod 25 in line with the final groove of the record. The phonograph then being started into action, the repeater turns with the record until the needle engages the rod 24, which holds the repeater from rotation with the record while the composition is being played, the spring fingers 19 of the clutch ferrule sliding on the spindle during this operation, and the repeater is so held from rotation by the sliding movement of the needle along the rod 24 until its end portion 25 is reached, at which time the needle reaches the end of the record and passes beyond said portion 25, thus permitting the repeater to rotate with the record and turntable. A relative motion is thus established whereby, as the needle remains in a fixed position, the repeater is turned until some point of the edge 13 of the flaring guide plate 5 of the repeater engages the needle, which enters the flaring guideway of the return groove and, through the continued motion of the repeater, traverses the full length of said groove and finally passes beyond the same into the recess 7, at which point the needle again engages the starting groove of the record and is in position to repeat the playing of the composition, whereupon a repetition of the above-described operation of the repeater occurs. Through the described action of the repeater, it will be obvious that the needle may be returned to the starting point for the playing of the composition on the record any desired number of times, that the repeater may be adjusted to make the starting point any point in the groove of the record, for the repeater playing of the entire composition or any part thereof, and that the repeater may also be adjusted in an easy, ready and convenient manner, for so regulating the action of the reproducer in connection with records of any size, from minimum to maximum.

The invention provides a simple, reliable and efficient type of repeating device which may be manufactured and sold at low cost, which may be applied, removed and adjusted for the purposes described with great ease and facility, and which may be used without injury to the record or parts of the phonographic machine. It will be observed that the body or plate 1 of the repeater is of unitary construction, together with the yoke 15, and employs in connection therewith only two additional independent parts, to wit, the

head 16 and stop rod 24, whereby a structure of simple form is provided which may be made as strong and rigid as desired and capable of being more or less roughly handled without liability of breakage or derangement. It will, of course, be understood that the device may be made as plain or as ornamental as desired, and it may be provided on its underside with a layer or separate contact portions of felt or other similar material for engagement with the face of the record to prevent the same from being scratched or otherwise marred.

Having thus fully described my invention, I claim:

1. A phonograph record repeater including a member having a needle return guideway, a head engageable with the turnable spindle and having a resilient portion and a non-resilient portion, a split spring yoke on said member slidably receiving the head and engaging the non-resilient portion thereof, and means for contracting the yoke and causing it to bind against the non-resilient portion of the head.

2. A phonograph record repeater comprising a body having a needle return groove, a head having a non-resilient portion and a friction clutch portion, the latter adapted to grip the turnable spindle, a longitudinally slotted yoke carried by said body and slidably engaging the non-resilient portion of the head, said yoke having its arms divided at one end for relative movement for clamping and releasing actions, and means engageable with the divided ends of the yoke arms for contracting said yoke arms for clamping en-

gagement with said fixed portion of the head.

3. A phonograph record repeater having a needle return groove, a head provided with a friction clutch member to engage the turnable spindle, a slotted yoke slidably engaging said head, and means independent of the head for fixing the yoke to the head.

4. A phonograph record repeater comprising a member having a needle return guideway, a head embodying a non-resilient portion and a resilient clutch portion, the latter engageable with the turnable spindle, a resilient yoke slidably engaging said head, and means for contracting the yoke in adjusted position about the head and fixing it thereto.

5. A phonograph record repeater comprising a member having a needle return groove, a head provided with a friction clutch for engagement with the turnable spindle, an oblong rectangular slotted yoke slidably engaging the head said yoke being split at one end, and means for contracting the split end of the yoke to clamp said yoke to the head.

6. A phonograph record repeater including a member having a needle return guideway, a head engageable with the turnable spindle and having a resilient clutch portion and a non-resilient portion, a yoke on said member slidably receiving the head and engaging the non-resilient portion thereof, and means for fixing the yoke in adjusted position to the non-resilient portion of the head.

In testimony whereof I affix my signature.

MANUEL HUMBERTO PÉREZ.
